UNITED STATES PATENT OFFICE

157,180

BAG SEALING UNIT

Cecil Miller, Pomona, Calif., assignor to Consumer-Pak Machine Co., Pomona, Calif., a corporation of California

Application August 31, 1948, Serial No. 148,395

Term of patent 14 years

(Cl. D55—1)

To all whom it may concern:

Be it known that I, Cecil Miller, a citizen of the United States of America, residing at 1100 East Second Street, city of Pomona, in the county of Los Angeles, State of California, have invented a new, original, and ornamental Design for a Bag Sealing Unit, of which the following is a specification, reference being had to the accompanying drawing, forming a part thereof.

Figure 1 is a front perspective view of a bag sealing unit, showing my new design;

Figure 2 is a top plan view of the unit shown in Figure 1;

Figure 3 is a front elevational view thereof;

Figure 4 is a side elevational view thereof; and Figure 5 is a bottom plan view thereof.

I claim:

The ornamental design for a bag sealing unit, as shown.

CECIL MILLER.
